FILLING MACHINE

Albert R. Thompson, Los Gatos, Calif., assignor
to Food Machinery Corporation, San Jose,
Calif., a corporation of Delaware

Application March 9, 1940, Serial No. 323,153

6 Claims. (Cl. 226—98)

This invention relates to machines for filling containers.

The invention will be disclosed as embodied in a machine for filling cans with tomato paste. However, it will be apparent after the disclosure that the invention could be embodied to advantage in machines for filling containers with any semi-liquid mixture or mushy material, or any viscous or pasty substance.

One object of the invention is to provide a filling machine of the multiple-valve, revolving-reservoir type with means for variably controlling the timing of the valves.

Another object of the invention is to provide a machine which will introduce viscous material into containers from an enclosed reservoir where a supply of the material is maintained under pressure and from which it is discharged through valves which are vented to the atmosphere.

Another object of the invention is to provide a machine which will fill the container under pressure to overflowing without loss of material.

Other objects will appear after the following disclosure of a machine in which the invention has been embodied.

In the drawings:

Fig. 1 is an elevation of the machine showing its connections to the supply system.

Fig. 2 is a vertical section through the machine itself, taken as indicated by arrows 2—2 in Fig. 5.

Fig. 3 is a vertical section through a valve.

Fig. 4 is a detail.

Fig. 5 is a plan view of the cam track.

Fig. 6 is a fragmentary elevation of the cam track. The direction of the view is indicated by arrows 6—6 in Fig. 5.

Figs. 7 and 8 are fragmentary sections, taken as indicated in Fig. 5.

Fig. 9 is diagrammatic development of the cam track.

A general description of the machine and the system in which it operates will be given first. The tomato paste is deposited in a supply tank 10 (Fig. 1) from which it is drawn by a pump 11 and forced through the pipe 12 into the reservoir 13. The reservoir has a lid 14 secured by clamps 15. The pump 11 maintains the pressure within the reservoir 13 above atmospheric. A series of valves 16 is arranged around the bottom of the reservoir. The cans 17 are carried in vertical alignment with the valves 16 in carriers 18 which are elevated by engagement of their rollers 19 with a cam track 20. The carriers 18 rotate in unison with the reservoir 13 about a vertical axis, as will presently be described. During its travel

around the machine each can 17 is raised into engagement with its valve 16, opening the valve by contact therewith. The paste is forced through the valve into the can. Air and excess paste displaced from the can are discharged through the pipes 21. The paste overflow collects in the trough 22 from which it is drawn through the pipe 23 by the pump 24 and returned to the tank 10 through the pipe 25.

10 The pressure in the reservoir 13 is determined by the height of the stand pipe 26 which also serves to maintain the pressure substantially constant by by-passing the paste to the tank. When the machine is started, the pet cock 27 (Figs. 1
15 and 2) is open to exhaust air from the reservoir and to avoid air lock which might prevent delivery of paste to the reservoir. When paste begins to issue from the pet cock 27 it is an indication that the reservoir is filled with paste and the machine
20 is ready to start filling cans. The valve 27 is then closed.

Proceeding now with the description of the machine itself, a supporting framework is provided which includes a base 28, vertical standards
25 29, and a cross piece 30 to which the downwardly-extending supply pipe 31 is secured. The central body 32 (Fig. 2) of the base 28 has a vertical bearing 33, a web 34, and a vertical flange 35, upon the upper edge of which the main cam track 20
30 is formed.

The cam track 20 (Fig. 2) has a lower-level portion 90 and an upper level portion 91. The angular extent of these portions is shown in the plan view in Fig. 5. The lower-level portion 90
35 is connected by an upwardly-inclined portion 92 with the upper-level portion 91 which extends from the radial line 93 to the radial line 94. A downwardly-inclined portion 95 connects the end of the upper-level portion 91 with the beginning
40 of the lower-level portion 90. An auxiliary cam track 96 is mounted on the upper-level portion 91. It comprises two arcuate segments 97, 98. Segment 97 is secured by screws 99 to the main cam track 20. Throughout its length the segment 97 is one-half the width of the cam track 20, as can be seen in the section Fig. 7, except at the end 100 (Fig. 5) where it extends the full width and has a bevel 101 (Fig. 6). The width of the segment 98 is also just half the width of the cam track 20, so that it can rest upon the track with a portion of its length in side by side relation with the segment 97, as shown in Figs. 5
50 and 8. The segment 98 is slidably mounted on track 20 by means of L-shaped pieces 102 (Fig.
8) welded thereto which embrace the flange 103

of the track. Set screws 104 serve to secure the segment 98 in adjusted position, and it will be apparent that by loosening these set screws, the segment can be adjusted lengthwise so as to vary the effective over-all length of the auxiliary cam track 96 for a purpose hereinafter to be described. The end 105 (Fig. 5) of segment 98 is beveled.

Journalled in the bearing 33 is a hollow shaft 37 upon which is shrunk the hub 38 (Fig. 2) of a circular table 39 having depending guides 40 formed integrally therewith. The can carriers 18 are secured to plungers 41 which slide in the guides 40. Each plunger has a stub shaft extending laterally therefrom upon which a cam follower 19 is journalled. Depending from the bottom of the reservoir 13 is a cylindrical portion 42 which is threaded onto the hub 38 at 43. It has a vertical slot at 44 and a clamping bolt 45 for securing the reservoir in any vertically adjusted position with respect to the table 39 for rotation therewith. The table is rotated by means of a ring gear 46 driven by a pinion 47 on shaft 48 which is driven from drive shaft 49 by worm 50 and wheel 51.

The drive shaft 49 (Fig. 1) has a pulley 52 for receiving power from a suitable source. When the pulley 52 is rotated, the train of gearing just described rotates the table 39 by means of ring gear 46 and the reservoir 13 rotates in unison with the table. The can carriers 18 are carried around by the table and are raised and lowered by the rollers 19 following the main cam track 20 and the auxiliary cam track 96. When the cans 17 are raised they open the lift valves 16, which will now be described.

As shown in Fig. 3 the valve body 53 has a passage 36 opening into the reservoir 13 at its upper end. The body 53 is cylindrical and a lift plate 54 is telescopically guided thereon by means of a cylindrical flange 55. Leakage through this telescopic joint is prevented by a rubber jacket 56. The upper flange 57 of the jacket 56 is held in contact with the flange 58 on the valve body by a compression spring 59 coiled around the valve and bearing against a washer 60. The lower flange of the jacket 56 is maintained in contact with the lift plate 54 by the spring 59 bearing against a washer 61.

The lift plate 54 has a port 62 which is adapted to be closed by the fixed valve head 63 when in engagement with the annular rubber seat 64 on the lift plate 54, as shown at the left in Fig. 2. The valve head 63 is threaded on a tube 65 (Fig. 3) which passes through a vertical bore in the valve body 53. A fitting 66 is secured to the upper end of tube 65. When the valve head 63 is screwed onto the tube 65 the collar 67 of the fitting 66 is drawn tight against the face 68 of the valve body to hold the tube 65 rigidly in place so that the valve head 63 is fixed with respect to the valve body 53.

The valve head 63 has a central passage 69 formed therein which communicates with the passage 70 in the tube 65. In order to extend this vent and overflow passage to the exterior of the reservoir a fitting 71 is mounted in an aperture in the wall 72 of the reservoir. There is an inclined passage 73 formed in the fitting 71, the inner end of which is connected to the passage 70 by a pipe 74 and suitable couplings 75, 76. The outer end of the passage 73 is closed by a plug 77 which may be removed to permit the vent passages 73, 74, 70, 69 to be cleaned out by steam, compressed air, or a flexible instrument. Communicating with the passage 73 is a passage 78

which extends laterally and then downwardly. The passage 78 opens to the atmosphere to vent air from the can. After the air is exhausted from the can excess paste is forced out the vent 5 passage and is discharged downwardly from the passage 78 into the trough 22.

The trough 22 is stationary. It encompasses the reservoir 13 (Fig. 1) and is supported by the standards 29. A sump 79 (Figs. 1 and 2) is formed in the trough at the discharge point where the pipe 23 is attached for the purpose described. In order to convey the paste which collects in the trough to the sump 79 wipers are attached to the fittings 71. The wiper has a rectangular blade 80 (Fig. 3) which fits in the trough 22. The blade is welded to a nut 81 (Figs. 3 and 4) which is threaded on a sleeve 82 which is threaded into the end of the passage 78. As the reservoir rotates, the wipers 80 carry the paste around the trough to the sump 79.

The operation is as follows: The tomato paste is put in the supply tank 10 (Fig. 1) from which it is transferred under pressure by the pump 25 to the rotating reservoir 13. Each can 17 is elevated by its carrier 18 until its rim 83 (Fig. 3) comes into engagement with the annular rubber seat 64 which forms a pressure-seal connection between the rim of the can and the lift plate 54, so that the paste cannot escape therebetween. As the can is elevated further it raises the lift 54 against the spring 59, removing the seat 64 from the fixed valve head 63 and opening the port 62.

35 The paste is forced from the reservoir 13 through the passage 36 in the valve body 53 out of the port 62 and then laterally over the top of the valve head 63 and radially toward the wall of the can through the annular discharge outlet 84 between the valve head 63 and the seat 64. The effective area of the outlet can be varied by adjusting the threaded connection 43 (Fig. 2). Raising the reservoir 13 from the table 39 decreases the size of the outlet 84, and vice versa.

50 In filling the can the paste is forced out of the outlet 84 and descends the wall of the can. Being viscous it builds up from the bottom and from the wall of the can, as indicated by the broken outline 85 in Fig. 2. The air pocket 86 shrinks as the paste closes in and the air escapes through the central opening 69 in the valve head 63 into the vent passage and out to the atmosphere. When the air is exhausted from the can and the can is full of paste, additional paste is forced in through the valve to displace paste up the vent passage to obtain a visible discharge 55 from the fitting 71 into the trough 22 as an indication that the can is full. The valve head 63 is proportioned in thickness and diameter to act as a displacement head, it being disposed below the rim of the can when the can is being filled, so that when the can is lowered away from the valve the paste will settle to the desired level below the rim.

60 The time required to fill each can will depend on several factors, namely: the pressure head on the valve; the speed of rotation of the table 39; the effective area of the discharge outlet 84; and certain other factors, such as the viscosity of the material. While the visible overflow into the trough is necessary and valuable as an indication that the can is filled, nevertheless, it is desirable to maintain this over-

flow at a minimum. This is accomplished by adjusting the auxiliary track 96, as will now be described.

The progress of the cans around the machine is indicated by the series of broken-line circles in Fig. 5. The can enters the machine in the direction of the arrow 110 where it is placed on a carrier whose roller is on the lower-level portion 90 of the main cam track 20. As the table rotates (clockwise in Fig. 5) the roller encounters the incline 92 (Figs. 5 and 9). When the roller reaches the upper level, the beginning of which is indicated by the radial line 93 in Fig. 5 and the corresponding vertical line 93 in Fig. 9, the carrier has elevated the can to the point where its rim 83 (Fig. 3) is in proximity to the rubber ring 64 on the lift 54. The carrier roller then rolls up the beveled end 101 (Fig. 6) of the segment 97 onto the auxiliary track 96, opening the valve. The filling continues until the roller arrives at the point 111 (Fig. 9) when the roller descends the bevel 105 on the end of the adjustable segment 98 onto the upper level 91 of the main track 20, closing the valve, as shown in Fig. 1. When the roller reaches the point 94 (Figs. 5 and 9) it descends the slope 95, lowering the can away from the valve. The filled can then leaves the machine in the direction of arrow 112 (Fig. 5).

Referring to Fig. 9, the time the valve is open is represented by the distance from 93 to 111. In practice the effective length of the auxiliary track may be varied by endwise adjustment of the adjustable segment 98 to locate the cut-off point 111 where minimum overflow is obtained. During the time from 111 to 94 (Fig. 9) the valve is closed. By closing the valve at an advanced point in the cycle additional time is allowed for material to drip from the valve into the can.

I have found that machines embodying my invention can be economically constructed and are reliable in operation. This I attribute to the relative simplicity and ruggedness of the mechanism required, as compared to machines heretofore designed for handling material, such as tomato paste. I have also found that the use of my invention in a filling machine provides a machine which has a high capacity, in that it will fill containers with viscous substances at a rapid rate in spite of the normally sluggish movement of such substances.

While I have described a particular embodiment of the present invention, it will be obvious that various changes and modifications may be made in the details without departing from the spirit of the present invention and the scope of the appended claims.

Having thus described my invention and in what manner the same may be used, what I claim as new and desire to protect by Letters Patent is:

1. A machine for filling containers with materials of high viscosity, comprising a supply tank, an enclosed reservoir, a pump to transfer material from said tank to said reservoir, a by-pass to return excess material to said tank and to regulate the pressure maintained on the material in said reservoir, a valve in said reservoir for exhausting air therefrom and for indicating the presence of an adequate supply of material therein, a plurality of lift-type filling valves each having means to establish a pressure seal connection with the opening in the container, and an overflow passage from each valve to the exterior of the reservoir having an outlet open to the atmosphere for exhausting air from the container and

for indicating by discharge of overflow material from the container that the container has been filled with the material.

2. A machine for filling containers with materials of high viscosity, comprising a supply tank, an enclosed reservoir, a pump to transfer material from said tank to said reservoir, a by-pass to return excess material to said tank and to regulate the pressure maintained on the material in said reservoir, a plurality of valved outlets in said reservoir, means on each outlet to establish a pressure-seal connection with the opening in the container, an overflow passage in each outlet to conduct excess material away from the container after the container has been filled with material under pressure, a conduit to collect the excess material from said overflow passages, and a pump to return the material in said conduit to said supply tank.
3. In a machine for filling cans, a rotary reservoir having filling valve units mounted in the bottom thereof, each unit comprising a valve body having a filling passage communicating with the reservoir, valve means to close the outlet of said passage comprising a valve head, a spring-pressed lift adapted to contact the rim of the can and be elevated thereby, and a seat for said valve head on said lift, a vent passage having an opening into the can through said head, said vent passage being provided by a pipe extending upwardly from the valve body into the reservoir and then through the wall of the reservoir to the exterior thereof and terminating in a depending end, a stationary trough underlying said depending ends of said vent pipes, and a wiper rotating with said pipes and fitting into said trough, whereby upon rotation of said reservoir the excess material from the cans will be discharged through said vent passages into said trough and conveyed around said trough to a discharge point by said wiper.
4. A machine for filling cans and the like with semi-liquid and pasty substances, comprising a supporting framework, an enclosed reservoir having filling valves in the bottom thereof, a series of can carriers beneath said valves, means to rotate said reservoir and carriers in unison, means including a cam track attached to said framework to raise and lower said carriers during each revolution, means to maintain a supply of the substance in said reservoir under substantially constant pressure, each of said filling valves having two passages therein, a filling passage to admit the substance to the can under pressure from the reservoir and an overflow passage to withdraw excess substance from the can, each of said filling valves having a lift plate which opens the valve when raised by a can, said plate having a seal which makes an air-tight connection with the rim of the can to prevent escape of the substance therebetween, said overflow passages in said filling valves discharging into an open trough secured to said framework, a pipe to withdraw the substance from said trough, and a wiper rotated in unison with said reservoir extending into said trough to sweep the substance discharged into said trough to said withdrawal pipe.
5. In a machine for filling cans with viscous substances, an enclosed reservoir, means to maintain a supply of the substance in said reservoir under pressure, filling valve units mounted in the bottom of said reservoir, each unit comprising a valve body having a filling passage communicating with the interior of said reservoir, a can-actuated lift valve to control the outlet of said filling passage, a vent passage, the lower end of

said passage opening into the can, said passage leading upwardly through said valve body and extending upwardly and outwardly through the wall of said reservoir to the exterior thereof, a removable plug to close the upper end of said passage, and a second vent passage, the inner end of said second passage communicating with said first vent passage adjacent the upper end thereof, the outer end of said second passage opening into the atmosphere.

6. A machine for filling open top containers with a viscous substance, comprising a supporting framework, an enclosed reservoir having a series of ports formed in the bottom thereof, a series of container carriers beneath said ports, means to rotate said reservoir and carriers in unison, means

for maintaining a supply of viscous substance in said reservoir under pressure, valve means normally closing said ports, means on said framework for raising said carriers during the united rotation of said reservoir and carriers to raise said containers with the open top thereof in engagement with the valve means for opening said ports, an open trough having an outlet formed therein and arranged on said framework concentric with said reservoir, vent means associated with said valve means for discharging excess substance into said open trough, a wiper extending into said open trough, and means for moving said wiper through the trough to urge the excess substance to the outlet formed in said trough.
